Primary Examiner — Wan Laymon*(74) Attorney, Agent, or Firm* — Hayes Soloway P.C.(57) **CLAIM**

The ornamental design for a bottle bottom, as shown and described.

DESCRIPTION

FIG. 1 is a front view of a bottle bottom showing our design; and,
FIG. 2 is a side perspective view of the bottle bottom.
The broken lines are for illustrate purposes and form no part of the claimed design.

1 Claim, 1 Drawing Sheet(56)
